PORTABLE HAND-HELD VACUUM CLEANER

Takeo Hori, Fukuoka, Japan, assignor to Matsushita
Electric Industrial Co., Ltd., Osaka, Japan, a corporation of Japan

Filed June 22, 1967, Ser. No. 7,566

Term of patent 14 years

(Cl. D49—14)

FIG. 3

FIG. 2

FIG. 1 is a plan view of a portable hand-held vacuum cleaner showing my new design;

FIG. 2 is a side elevational view thereof,

FIG. 3 is a top and front perspective view thereof on enlarged scale, and

FIG. 4 is a bottom and rear perspective view thereof also on enlarged scale.

The dominant features of my design reside in the portions shown in full line.

I claim:

The ornamental design for a portable hand-held vacuum cleaner, as shown and described.
